UNITED STATES PATENT OFFICE

OTTO J. KUHLKE, OF AKRON, OHIO

APPARATUS FOR THE MANUFACTURE OF GOLF BALLS

Original application filed May 31, 1928, Serial No. 281,845. Divided and this application filed April 12, 1929. Serial No. 354,502.

The present invention relates to the manufacture of golf balls and particularly to the manufacture of the resilient rubber core.

In the manufacture of the standard golf ball, the center or core of the ball is wound with a thread rubber of high grade rubber, the thread being wound under tension to impart the required life and resilient properties to the ball. The resilient mass of rubber thus obtained is of comparatively short life and due to the method of winding, soon loses its elastic qualities, a result which may be observed in cutting a golf ball, the thread rubber being limp and lifeless.

It is the object of the present invention to devise a new and improved apparatus for winding or overlaying the rubber upon the core so as to secure a better and more lively construction of the ball. This is accomplished by the device illustrated and described; although the details of the apparatus are not essential and may be varied within the scope of the invention.

The product of the machine and process is a new form of golf ball which forms the subject matter of copending application Serial No. 281,845, now Patent No. 1,715,661, dated June 4, 1929, of which this application is a division.

Briefly stated, the invention comprises the wrapping or winding of a tube of rubber about the core of the ball, the tube being stretched to secure the proper resiliency of the rubber and the winding taking place about the core in such a way that a spherical center is obtained.

In the drawings:

Figure 1 is a general plan view of an apparatus appropriate for carrying out the invention, the view being a longitudinal section through the winding mechanism and being taken at the commencement of the winding operation;

Figure 2 is a view of the mold or rolling tube showing the means by which the rubber cover is given the preliminary stretch;

Figure 3 is a detail of the head at the commencement of the winding operation;

Figure 4 is a view showing the initiation of the rolling operation;

Figure 5 is a further view showing details of the mechanism;

Figure 6 is a cross-section on the line 6—6 of Figure 3; and

Figure 7 is a section on the line 7—7 of 55 Figure 1.

The apparatus comprises a forming mold or tube 1, which is in the form of a long, tapered or conical chamber, the smaller end being of substantially the same inner diameter as the core 2 of the golf ball and the larger end of substantially the same diameter as the completely wound or wrapped center.

The core is wound with a sheath or tube of thin, high grade rubber 3 which is in normal or unstretched condition as shown, substantially one-fourth of the diameter and length of the tube or sheath before stretching preparatory to the wrapping operation although the percentage of stretch may be varied within wide limits, and which is tapered to substantially the same extent as the mold. The smaller end of the tube is stretched over the core and fastened to the core by being cemented about its edges. 65

The tube with the ball therein is then placed in the mold and the larger end of the tube is stretched over a cap 5 which is later mounted on a guide for movement to clamp the mouth of the tube against the mold. 70

Air under pressure is admitted through an inlet pipe 7 to the interior of the cap and to the interior of the tube, the pressure being sufficiently high to stretch the tube outwardly against the wall of the mold and to drive the core to the far end of the mold, thereby giving the required longitudinal stretch. This causes the tube 3 to be stretched equally in all directions. At this stage of the operation the smaller end of the mold is open to permit escape of air in front of the core. The stretched sheath is shown in Figure 1. 85

In the smaller end of the mold is located the movable plunger 10 which is mounted in the forward end of a push rod or shaft 11 mounted for sliding movement in a stuffing box 12 on the end of the mold. The inner end of the head is cut away upon an oblique plane and is provided with a wear plate 14 on which is mounted the pusher head 15, this head being 95 100

5 rotatable upon a center pin 16 and held against the wear plate by a spring 18, a ball race 20 being interposed between the parts 14 and 15. The aperture 21 about the pin 16 is cut away as shown to permit freedom of movement to the head.

10 To the pusher 15 are pivoted a plurality of swinging fingers 22, the outer ends of which are provided with rollers 23. Six of these rollers are shown, their function being to engage the core 2 and roll it in the mold. If the core were to be pushed without changing its axis of rotation, the tube would roll up on the ball in a definite zone. It is desirable to 15 change the axis of rotation of the ball constantly during the rolling operation in order to distribute the folds in the jacket evenly about the entire surface of the core. For this reason the plunger is rotated as it is moved through the mold, while the head is non-rotative. 20

25 To rotate the plunger, the shaft 11 is rotatably mounted in a cross head 25, which is supported on guide rod 26. The cross head is moved by a piston rod 28 movable in a fluid pressure cylinder 30 paralleling the mold and actuated by pressure admitted at the ends of the cylinder through a control valve 32 from a main air tank 34 which also supplies the air 30 for the inlet 7.

35 Supported in the head 25 is a rotatable threaded shaft 36 which is engaged by a pin 37 on the mold. The shaft 36 is geared to the shaft 11 through gearing 38. It will thus be seen that as the carrier 25 advances, rotation will be imparted to the shaft 11 from the threaded shaft 36 and intermeshing gearing. This will tend to rotate the head. Due to the 40 angular setting of the head the rotation of the plunger 10 will rock the plate and thus advance the rollers 23 into contact with the core in succession around the interior of the chamber. This will apply a continuous force to the core in a spiral path and the direction of 45 rotation of the core will be constantly changed as a result thereof.

50 During the wrapping or rolling process it is necessary to keep the envelope or tube of rubber at a constant degree of expansion or tension. It may be desirable to equalize the pressure upon opposite sides of the core which can be done through a connecting pipe 40. The pressure in the supply tank is maintained uniform through any suitable accumulator.

55 It will be seen that when the ball is forced to the larger end of the mold it will have built up thereon a multiple series of crossing folds or flutes of rubber under a uniform tension which gives the required elasticity to the golf ball center. With the tubular jacket or sheath there are no exposed edges of rubber as encountered in the usual thread rubber winding, and the rubber sheath, therefore, cannot fray or break down at the edges which is the cause of the thread rubber losing its elasticity.

and its life and resiliency. After the winding operation is completed the cap 5 is removed and the wound ball discharged from the mold. It is then covered and completed in any well known or accepted manner. The 70 invention may be applied to other playing balls or wherever a highly resilient spherical object is required.

What is claimed is:

1. In an apparatus for the purposes set forth, means for holding a tube of rubber in tubular form with its inner surface unobstructed, and means for rolling a core axially and internally of the tube whereby the rubber is rolled up about the core. 75
2. In an apparatus for the purposes set forth, means for maintaining a tapering tube of rubber distended and under tension, and means for rolling a core from the smaller to the larger end of the tube. 80
3. In an apparatus for the purposes set forth, means for holding a tube of rubber in tubular form with its inner surface unobstructed, means for rolling a core axially of the tube whereby the rubber is rolled up about 85 the core and means for simultaneously rolling the core about its center. 90
4. In an apparatus for the purposes set forth, means for maintaining a tapering tube of rubber distended, and means for forcing a core from the smaller to the larger end of the tube and simultaneously rolling the core about its center. 95
5. In an apparatus for the purposes set forth, an elongated mold having a conical bore, means at the larger end of the tube for closing the same and for clamping a tube of rubber, means for expanding the tube of rubber against the interior of the bore, and a pusher movable along the bore to roll a core 100 inwardly of the tube. 105
6. In an apparatus for the purposes set forth, an elongated mold having a conical bore, means at the larger end of the tube for closing the same and for clamping a tube of rubber, means for expanding the tube of rubber against the interior of the bore, and a pusher movable along the bore to roll a core 110 inwardly of the tube, the pusher being provided with means to change the direction of 115 rotation of the core.
7. In an apparatus for the purposes set forth, an elongated mold having a bore therein, means for holding a tube of rubber against the interior of the bore, and a pusher movable 120 through the bore and having means to engage a core to force it into the tube.
8. In an apparatus for the purposes set forth, an elongated mold having a bore therein, means for holding a tube of rubber against 125 the interior of the bore, and a pusher movable through the bore and having means to engage a core to roll it inwardly of the tube and simultaneously to change the direction of rotation of the core. 130

9. In an apparatus for the purposes set forth, an elongated mold having a bore therein, means for holding a tube of rubber against the interior of the bore, and a pusher movable through the bore and having means to engage a core to roll it inwardly of the tube and simultaneously to change the direction of rotation of the core, said means comprising a head having a plurality of fingers and means to bring the fingers in contact with the core in succession.

10. An apparatus for the purpose set forth comprising a mold having an elongated bore, a plunger movable along the bore, a pusher head on the plunger, a plurality of fingers on the head, and means for oscillating the head to bring the fingers successively in contact with a core.

11. An apparatus for the purpose set forth comprising a mold having an elongated bore, a plunger movable along the bore, a pusher head on the plunger, said head having a plurality of fingers to engage a core, and means for bringing the several fingers into operation successively during the movement of the plunger.

12. An apparatus for the purpose set forth comprising a mold having an elongated bore, a plunger movable along the bore, a pusher head on the plunger, said head having a plurality of fingers to engage a core, means for bringing the several fingers into operation successively during the movement of the plunger, and means to hold a sheath of rubber in stretched condition within the bore.

13. An apparatus for the purpose set forth comprising a mold having an elongated bore, a plunger movable along the bore, a pusher head on the plunger, said head having a plurality of fingers to engage a core, means for bringing the several fingers into operation successively during the movement of the plunger, and a fluid supply connected to the interior of the mold to hold a sheath of rubber in stretched condition within the bore.

OTTO J. KUHLKE.
